(57) **CLAIM**

The ornamental design for a sample collection device, as shown and described.

DESCRIPTION

FIG. 1 is a perspective view of a sample collection device. FIG. 2 is a front (back) view of the sample collection device. FIG. 3 is a top view of the sample collection device. FIG. 4 is a bottom view of the sample collection device. FIG. 5 is a left side view of the sample collection device. FIG. 6 is a cross-sectional view through line 6-6 of the sample collection device shown in FIG. 5. FIG. 7 is a left side exploded view of the sample collection device. FIG. 8 is a perspective exploded view of the sample collection device. FIG. 9 is a top view of the homogenization cap of the sample collection device. FIG. 10 is a bottom view of the homogenization cap of the sample collection device. FIG. 11 is a perspective view of the pusher cap shown of the sample collection device. FIG. 12 is a top view of the pusher cap of the sample collection device. FIG. 13 is a bottom view of the pusher cap of the sample collection device. FIG. 14 is a front (back) view of the pusher cap of the sample collection device. FIG. 15 is a left side view of the pusher cap of the sample collection device. FIG. 16 is a perspective view of the collector tube of the sample collection device. FIG. 17 is a front (back) view of the collector tube of the sample collection device. FIG. 18 is a left side view of the collector tube of the sample collection device. FIG. 19 is a top view of the collector tube of the sample collection device; and, FIG. 20 is a bottom view of the collector tube of the sample collection device.
